R. M. PENNING.
ICE MARKING MACHINE.
APPLICATION FILED DEC. 20, 1920.

1,406,999.

Patented Feb. 21, 1922.

UNITED STATES PATENT OFFICE.

RICHARD M. PENNING, OF CLAYTON, MISSOURI.

ICE-MARKING MACHINE.

1,406,999.

Specification of Letters Patent. Patented Feb. 21, 1922.

Application filed December 20, 1920. Serial No. 432,024.

To all whom it may concern:

Be it known that I, RICHARD M. PENNING, a citizen of the United States, residing at Clayton, in the county of St. Louis and 5 State of Missouri, have invented a new and useful Improvement in Ice-Marking Machines, of which the following is a specification.

My invention relates to ice-marking machines and has for its principal object to devise a machine that will operate automatically and that will accurately mark blocks of ice or other materials with transverse and longitudinal grooves. The invention 10 comprises a carriage provided with cutters or markers and arranged to be operated by the weight of the blocks of ice being marked. The invention further consists in the tool for cutting or marking the blocks; 15 and it also consists in the parts and combinations of parts hereinafter described and claimed.

In the drawings, which form part of this specification and wherein like reference 25 characters indicate like parts in the several views,

Fig. 1 is a side elevation of an ice-marking machine embodying my invention, showing a block of ice thereon, the dot and dash 30 lines indicating the location of the marks made by the cutters;

Fig. 2 is a sectional view on the line 2—2 of Fig. 1;

Fig. 3 is a side elevation of one of the 35 cutters; and

Fig. 4 is a front elevation of the same.

A truck or carriage 1 is provided with longitudinally disposed plates or bars 2 adapted to support a block of ice 3 and, in effect, 40 constitutes part of an ice conveyor system. Said carriage has flanged or grooved wheels 4 which run on an inclined track 5. When the carriage 1 is at one end of the trackway 5, it is adjacent to the end of an ice conveyor 6 (in practice, the conveyor leading from the tank room) and in position to receive a block 45 of ice from the conveyor, and when it is at the other end of the trackway, it is adjacent to another conveyor 7 (in practice, one leading to the storage room), and in position to discharge the block of ice thereon.

The carriage is provided with uprights 8, preferably angle irons, which are framed together at the top by framing members 9. 55 Cutter bars 10 having grooves 11 in their

ends which engage a flange of said uprights 8 are arranged at the sides of said carriage. Cutters or marking tools 12, which will be hereinafter described, are secured to said cutter bars 10 in position to mark the block 60 of ice 3 in the carriage. Similar cutters 12 are mounted on the uprights at the discharge end of the carriage.

Ropes or cables 13 secured to eye-bolts 14 near the ends of the cutter bars 10 pass over 65 sheaves 15 mounted on the longitudinal framing members 9. The ends of said cables 13 are secured to hooks 16 fastened to the wall 17 or to any suitable support. The cables 13 are provided with turnbuckles 18 70 whereby they may be adjusted. When the carriage is adjacent to the first conveyor 6, the cutter bars are slightly below the level of the ice supporting slats 2. A U-shaped stop bar 19 is provided at the discharge 75 end of the carriage for holding the block of ice 3 thereon. The ends of said stop bar are pivotally secured to the longitudinal framing members 9 and the base is preferably supported by a chain 20 or the like secured 80 thereto and to a framing member 9. Said bar has projecting portions 21 in position to be engaged by the cutter bars 10 near the end of their upward movement, whereby the stop bar 19 is raised to clear the block of 85 ice 3.

The cutter bars 10 are provided with beveled grooves 22 in which are slidably mounted guide blocks 23 to which are secured the cutters 12, each of which comprises 90 a piece of spring metal doubled on itself. Each cutter is provided with a cutting or grooving tool 24 near the free end thereof, and with longitudinal slots 25, through which project beveled wheels 26 which are 95 journaled in a bearing block 27 attached to the back side of said cutter, as by screws 28. Obviously, the distance that these marking wheels 26 project can be regulated by inserting shims 27a between the cutter and the 100 bearing block.

A lever 29 extends longitudinally of the carriage and is pivotally secured to a cross-piece 30 arranged on the under side of said carriage. Said lever 29 has a hook 31 at 105 the receiving end of the carriage. Near the discharging end of the carriage, said lever is bent upwardly and projects above the ice carrying bars at 32, in position to be depressed by a block of ice 3 on the carriage. 110

The end portion of said lever 33 is bent downwardly and a hook 34 is pivotally secured thereto.

The operation of the machine is as follows:

Assuming that the carriage 1 is at the upper end of the inclined track 5, the hook 31 engages a cross-piece 35 provided therefor at the end of the conveyor 6. A block of ice 3 10 is discharged from the conveyor 6 onto the carriage, which is just large enough to accommodate it. When the forward end of the block of ice 3 reaches the end of the carriage 1, it is engaged by the stop bar 19 and 15 prevented from leaving the carriage. The pressure of the ice on the projecting portion 32 of the lever disengages the hook 31 from its cross-piece 35, and the weight of the ice causes the carriage to travel down the inclined track. As the carriage travels, the cutter bars 10 are moved upwardly by reason 20 of the fact that the ends of the cables 13 are fixed. As the cutter bars 10 move upwardly, the cutting tools 12 cut transverse grooves 25 in the sides of the blocks of ice, as indicated by the dot-and-dash lines in Fig. 1 of the drawings. As the carriage nears the second conveyor 7, the cutter bars 12 engage the 30 projections 21 on the stop bar 19 and raise said bar, leaving the block of ice free to slide 35 off the carriage. When the carriage reaches the second conveyor, it strikes against a spring bumper 36 secured thereto. The second hook 34 engages a cross-piece 37 secured 40 to the second conveyor 7 and prevents the carriage from moving back. The block of ice 3 now slides off the carriage, and as it does so, the cutters 12 on the uprights make longitudinal grooves therein. When the ice 45 leaves the carriage and the pressure on the projecting portion 32 of the lever 29 is relieved, the weight of said lever causes the end thereof at the receiving end of the carriage to drop, raising the other end and releasing the hook 34, so that the carriage is 50 free to travel backwards. The weight of the cutter bars causes the carriage to travel up the inclined track until it reaches the conveyor 6 and is in position to receive another block of ice.

The number and location of the cutters or marking tools may be changed at will to cut grooves in blocks of ice. The grooves in a block of ice facilitate the operation of cutting the block into pieces, as the ice tends to split along the grooves, and thus the size or weight of the pieces into which the block may be cut can be predetermined with a fair degree of accuracy in contrast with the 55 guesswork now commonly prevalent.

It is obvious that changes may be made in the construction and arrangement described without departing from my invention, and I do not wish to be limited to the precise 60 construction shown.

What I claim is:—

1. A device for marking blocks of ice and the like comprising a frame having scoring elements thereon, some of such elements being stationary and located in position to score a groove in the block as it moves past them and other of said elements being movable in position to score said block transversely with relation to said first mentioned grooves, the movement of said last mentioned scoring elements being actuated by a block of ice on said frame. 75

2. A device for marking blocks of ice and the like comprising a guiding and supporting frame having scoring elements thereon, some of such elements being fixed to said frame and adapted to score a groove in the block as it moves past them and other of said elements being movable with respect to said frame and adapted to score said block 85 transversely with relation to said first mentioned grooves, the relative movement of said last mentioned scoring elements being actuated by a block of ice on said frame.

3. A device for marking blocks of ice and the like comprising a movable guiding and supporting frame having scoring elements thereon, some of such elements being fixed to said frame and adapted to score a groove in the block as it moves past them and other 95 of said elements being movable with respect to said frame and means for actuating said movable elements to score said block transversely to said first mentioned grooves during the travel of said movable guiding and 100 supporting frame, said actuating means comprising a block of ice on said frame.

4. A device for marking blocks of ice and the like comprising a movable supporting and guiding frame, having scoring elements 105 thereon, some of such scoring elements being fixed to said frame and adapted to score a groove in the block as it moves past them and other of said elements being movably mounted on said frame and adapted to be 110 actuated by movement of said frame during its travel to score said block transversely to said first mentioned grooves, a block of ice thereon actuating the movement of said frame. 115

5. An inclined track, ice conveyors terminating at each end of said track, a wheeled carriage on said track adapted to receive a block of ice from the conveyor at the upper end of said track and discharge it onto the conveyor at the lower end thereof, cutters on said carriage movable across the sides of said block of ice to mark transverse grooves therein and other cutters arranged on said carriage to cut longitudinal grooves in the 125 sides of said block as it leaves the carriage.

6. An inclined track, ice conveyors terminating at each end of said track, a wheeled carriage on said track adapted to receive a block of ice from the conveyor at the upper 130

end of said track and discharge it onto the conveyor at the lower end thereof, releasable means for holding said carriage in juxtaposition to said first mentioned conveyor until 5 the block of ice is entirely on said carriage, said means being released by the block of ice itself, cutters on said carriage movable across the sides of said block of ice to mark transverse grooves therein and other cutters 10 arranged on said carriage to cut longitudinal grooves in the sides of said block as it leaves the carriage.

7. An inclined track, ice conveyors terminating at each end of said track, a wheeled 15 carriage on said track adapted to receive a block of ice from the conveyor at the upper end of said track and discharge it onto the conveyor at the lower end thereof, cutters on said carriage movable across the sides of said 20 block of ice to mark transverse grooves therein and other cutters arranged on said carriage to cut longitudinal grooves in the sides of said block as it leaves the carriage, and means for returning said carriage to the upper 25 end of said track after the block of ice has been discharged.

8. An inclined track, a carriage thereon adapted to receive a block of ice, cutter carrying means mounted on said carriage so as 30 to be movable across the surface of a block of ice on said carriage, and cutters on said carrying means, said carriage being set in

motion by the weight of the block of ice and the movement of the carriage operating said cutter carrying means. 35

9. A carriage adapted to receive a block of ice and discharge it later, means for holding such block of ice thereon, cutters arranged to move across the face of such block of ice to mark grooves therein, and other cutters arranged on said carriage to mark additional grooves in said block of ice as it leaves said carriage. 40

10. A cutter for ice marking machines, comprising a strip of spring metal bent to 45 substantially inverted U-form, said cutter having a cutting tool near one end thereof, and a plurality of slits adjacent to said cutting tool, a bearing block secured to said cutter and beveled wheels pivotally mounted 50 in said bearing block, said wheels projecting through the slits in said cutter.

11. A cutter for ice-marking machines, comprising a strip of spring metal bent to 55 substantially inverted U-form, said cutter having a scoring device near one end thereof, and a plurality of slits adjacent to said scoring device, and beveled wheels pivotally disposed on said cutter, said wheels projecting through said slits therein. 60

Signed at St. Louis, Mo., this 18th day of December, 1920.

RICHARD M. PENNING.
